Chas. C. Gille ATTORNEY

UNITED STATES PATENT OFFICE.

OTTO J. GASAU, OF BROOKLYN, NEW YORK, ASSIGNOR TO GASAU-THOMPSON COMPANY, INC., OF BROOKLYN, NEW YORK, A CORPORATION OF NEW YORK.

MATTRESS FABRIC.

1,373,232.

Specification of Letters Patent. Patented Mar. 29, 1921.

Application filed July 23, 1920. Serial No. 398,333.

To all whom it may concern:

Be it known that I, Otto J. GASAU, a citizen of the United States, and a resident of Brooklyn, in the county of Kings and State 5 of New York, have invented certain new and useful Improvements in Mattress Fabrics, of which the following is a specification.

The invention pertains more particularly 10 to mattress fabrics or spring bed bottoms, and it consists in the novel features and structure hereinafter described, and particularly pointed out in the claims.

The mattress of my invention comprises 15 a novel mattress fabric formed of transverse sections suitably hooked together and preferably secured to usual head and foot bars by helicals and to side members by links. One object of this invention is to facilitate 20 the manufacture and assembling of the sections of a wire mattress fabric and to provide sections which, when assembled, will create a diamond effect throughout the fabric, the openings or meshes in the fabric 25 being of true diamond outline and the defining wires in the assembled fabric being extended on substantially continuous straight crossing lines diagonally of the mattress.

I form each transverse section of the mattress, by preference, from one integral rod 30 of wire bent zigzag to define between each two adjacent members thereof the outline of one-half of a diamond figure, and at the inner apex or junction point between each 35 two adjacent members I form a double-strand hook, while at the outer apex point between each two adjacent members I form an eye. The eyes of one transverse section 40 of the mattress fabric are adapted to be caught upon the hooks of the next adjacent section of the mattress fabric and in this way the mattress may be built up from the transverse sections with the least possible delay. The formation of the transverse sections 45 of the mattress is such that said sections may be readily and durably manufactured and, when assembled, present a spring structure of uniform appearance and one in which strains are equalized throughout the 50 mattress in a manner tending to render the mattress mechanically and otherwise of advantageous character.

The invention will be fully understood from the detailed description hereinafter

presented, reference being had to the accompanying drawings, in which:

Figure 1 is a top view, partly broken away, of a wire mattress embodying the features of my invention;

Fig. 2 is a detached top view, partly broken away, of one transverse section of the same;

Fig. 3 is a longitudinal vertical section, on a larger scale, through a portion of the mattress, taken on the dotted line 3—3 of Fig. 1;

Fig. 4 is an enlarged view, partly broken away, showing the double-hook end on one section of the mattress and illustrating by dotted lines the connection of said hook with 70 an eye on an adjacent section of the mattress and the effect on the double-hook of a tension placed on the spring mattress, such tension acting to draw the adjacent side members of the hook in a direction toward 75 each other, as the dotted lines indicate;

Fig. 5 is a top view, corresponding with Fig. 1, illustrating a modified construction of the transverse sections of the mattress; and

Fig. 6 is a top view, partly broken away, of one of the transverse sections of the mattress shown in Fig. 5.

The wire fabric is connected at its ends by helicals 10 to end rails 11 and at its 85 sides by links 12 with side members of suitable type 13 whose ends are connected by helicals 14 with the aforesaid end rails 11.

My invention pertains more particularly to the wire fabric, and this fabric will be 90 connected with the usual types of frames employed by manufacturers of wire mattresses, these frames, as is well known, comprising rigid side bars and rigid end bars connected therewith and usually arranged on a higher 95 elevation than the side bars, the entire frame being adapted to be handled as a unit and to rest upon the side bars of the bedstead, in the construction of a five-part bedstead, or with the head and foot members of the bedstead in the construction of a three-part bedstead. The supporting frames for wire mattresses being of well known character, it is not deemed necessary to particularly show and describe the same 100 herein.

The fabric of my invention comprises a series of interconnected transverse sec-

tions 15, 16, all of the sections 15 being alike and all of the sections 16 being alike, and the sections 15, 16 being alike with the exception that at their outer side ends the wires of the sections 16 are formed into eyes 17 to receive the side ends of the sections 15 and the inner ends of the links 12 by which the fabric may be secured to the side or edge members 13.

10 Each section 15 is formed from a single rod of wire bent into zigzag form to define equal members sharply defining the shape of one-half of a diamond figure, said half-diamond shapes alternately extending inwardly, as at 18, and outwardly, as at 19, and said shapes 18, 19 being coequal and presenting straight though diverging equal edges or members 20, 20. At the outer apex ends of the mesh shapes 18, the wire of each 15 section 15 is bent to form eyes 21 which are preferably closed by twisting the wire at what would otherwise be the open side of the eye, this closing of the eyes 21 serving to strengthen the fabric without adding 20 material expense thereto; and at the inner apex ends of each shape 19 of the sections 15 I bend the adjacent portions of the wire members 20 into a double-hook 22 which has parallel closely related longitudinal 25 sides 23 of such length as to admit, under strains, of a slight yielding of the same toward and from each other, as indicated by the dotted and full lines in Fig. 4. The side members 20 of the shapes 19 are 30 brought into close relation to each other and then bent longitudinally to form the hooks 22, said hooks when thus formed with the said side members 20 brought nearly together serving as very durable connecting 35 means for the adjacent transverse section 16 of the fabric without destroying the true diamond effect I seek to maintain throughout the entire extent of the fabric. The wire of each section 15 at its 40 side ends is formed into a hook 24 to engage the eyes 17 at the ends of the next adjacent fabric section 16. Each transverse fabric section 15 is thus of zigzag outline defining equal half-diamond spaces 45 between the adjacent zigzag members thereof and each of said spaces at its outer apex end is formed with an eye 21 and at its inner end with the double-hook 22, the eyes 21 being preferably closed by the 50 twisting of the wire, as shown at the upper end of Fig. 1, and said hooks being preferably formed of closely related parallel side members which are, by preference, slightly separated from each other.

55 The transverse sections 16 correspond substantially throughout with the sections 15, with the exception that the zigzag portions of the sections 16 are reversed from those of the transverse sections 15 so that in 60 matching the spaces of the sections 15, 16,

true diamond-shaped meshes are created. The outer apex ends of the zigzag members of the sections 16 are formed with eyes 21 corresponding with the eyes 21 of the sections 15, and at their inner apex ends the members of the sections 16 are formed with the double-hooks 22 corresponding with the double-hooks 22 of the members of the sections 15. The eyes 21 of the members of the section 16 are engaged upon the hooks 22 of the members of the adjacent section 15, and the double-hooks 22 of each section 16 are engaged by the eyes 21 of the next adjacent transverse section 15, as will be clearly understood on reference to Fig. 1. The only difference between the sections 15, 16, with the exception of their reverse order, is that at its ends the section 15 is formed with hooks 24 and the section 16 is formed at its ends with eyes 17 to engage said hooks 24 and also receive the inner ends of the links 12. The sections 15, 16 are therefore substantially alike in all essential respects, and in the finished fabric said sections are arranged in reversed order so that the zigzag spaces of the section 15 and the zigzag spaces of the section 16 may open into one another and form true diamond mesh outlines. The zigzag members of the sections 15, 16 are at equal angles, and hence when all of the sections 15, 16 have been connected together to form the mattress or spring fabric, said members extend along substantially continuous crossing diagonal lines, whereby strains exerted on the fabric are distributed along said diagonal lines, which are substantially unbroken or continuous throughout the fabric. The eyes 21 extend outwardly beyond the apexes of the zigzag shapes of the sections 15, 16 and are as small as may be consistent with the ready assembling of the parts of the fabric, and the hooks 22 extend inwardly at the apex points of the sections 15, 16 alternating with the planes of said eyes and have their sides brought as close together as may consistently be done so as to increase the strength and resisting qualities of the fabric and preserve the diagonal formation of the lines defining the diamond-shaped meshes of the fabric. The side members 23 of the hooks 22 are preferably slightly separated so that in the event of strains on the fabric, said sides may, at their inner ends, yield with the sides of the zigzag bends of the sections, thereby relieving the fabric of a rigidity it might otherwise have.

Figs. 5 and 6 illustrate a modification of the structure, said modification residing wholly in the fact that the eyes at the outer apex ends of the fabric sections are not closed by the twisting of the wire in the manner shown in Figs. 1 and 2. In other respects the construction shown in Figs. 5 and 6 is the same as that presented in Figs. 130

1 and 2, and therefore to avoid needless explanation I number Figs. 5 and 6 with the same numbering employed on Figs. 1 and 2, with the exception that the eyes numbered 5 21 in Figs. 1 and 2 are, in Figs. 5 and 6, numbered 30. The sections of the fabric shown in Figs. 5 and 6 define the same diamond outlines presented in Fig. 1 and said sections are assembled in the same manner that the sections shown in Fig. 1 are 10 brought together and for the same purpose. I present Figs. 5 and 6 merely to indicate that I do not in every instance desire to be limited to the closing of the eyes of the respective sections by the twisting of the wire 15 to accomplish that purpose.

The fabric composed of the sections 15, 16 is of particular advantage in that said sections form independent elongated units 20 and may be easily assembled to form a fabric of not only ornamental configuration, but one possessing substantially continuous crossing diagonal lines capable of resisting strains and not liable to undue sagging. I 25 regard it as particularly important that the wire members of the assembled units extend on substantially continuous diagonal crossing lines creating the diamond-shaped meshes and lines of resistance extending diagonally of the fabric in crossing directions and being substantially unbroken, so 30 that the lines of resistance are substantially directly through the zigzag side members of the portions of the respective units or 35 sections of the fabric.

What I claim as my invention and desire to secure by Letters Patent is—

1. A mattress fabric comprising a series of parallel elongated wire sections interengaged with one another in series, each section being formed of a rod of wire bent zigzag to define a series of corresponding alternately reversed space-meshes of the shape of one-half of a diamond figure and said 40 rod at the apexes of said figures opening in one direction being formed into an eye and at the apexes of said figures opening in the opposite direction into a double hook, and said sections being alternately reversely arranged 45 with the one-half diamond figures of one section matching the one-half diamond figures of the adjacent section to complete meshes of diamond-figure outline, and the hooks at the apexes of the members of one 50 set of alternate sections being engaged with the eyes at the apexes of the members of the other set of alternate sections, and the side members of said meshes defining substantially continuous crossing diagonal lines 55 extending throughout the fabric, said eyes being extended outwardly of the apexes of their contiguous one-half mesh-figures and closed at their inner ends at said apexes by the twisting of the opposite portions of the 60 wire thereat together, and said hooks being extended inwardly of the apexes of their contiguous one-half mesh-figures.

2. A mattress fabric comprising a series of parallel elongated wire sections interengaged with one another in series, each section being formed of a rod of wire bent zigzag to define a series of corresponding alter- 65

nately reversed space-meshes of the shape of one-half of a diamond figure and said rod at the apexes of said figures opening in one direction being formed into an eye and at the apexes of said figures opening in the 70 opposite direction into a double hook, and said sections being alternately reversely arranged with the one-half diamond figures of one section matching the one-half diamond figures of the adjacent section to complete meshes of diamond-figure outline, and the hooks at the apexes of the members of one set of alternate sections being engaged with the eyes at the apexes of the members of the other set of alternate sections, and the 75 side members of said meshes defining substantially continuous crossing diagonal lines extending throughout the fabric, said eyes being extended outwardly of the apexes of their contiguous one-half mesh-figures and 80 said hooks being extended inwardly of the apexes of their contiguous one-half mesh-figures.

3. A mattress fabric comprising a series of parallel elongated wire sections interengaged with one another in series, each section being formed of a rod of wire bent zigzag to define a series of corresponding alternately reversed space-meshes of the shape of one-half of a diamond figure and said rod 90 at the apexes of said figures opening in one direction being formed into an eye and at the apexes of said figures opening in the opposite direction into a double hook, and said sections being alternately reversely arranged 95 with the one-half diamond figures of one section matching the one-half diamond figures of the adjacent section to complete meshes of diamond-figure outline, and the hooks at the apexes of the members of one 100 set of alternate sections being engaged with the eyes at the apexes of the members of the other set of alternate sections, and the side members of said meshes defining substantially continuous crossing diagonal lines 105 extending throughout the fabric, said eyes being extended outwardly of the apexes of their contiguous one-half mesh-figures and closed at their inner ends at said apexes by the twisting of the opposite portions of the 110 wire thereat together, and said hooks being extended inwardly of the apexes of their contiguous one-half mesh-figures.

4. A mattress fabric comprising a series of parallel elongated wire sections interengaged with one another in series, each section being formed of a rod of wire bent zigzag to define a series of corresponding alternately reversed space-meshes of the shape of one-half of a diamond figure and said rod 120 at the apexes of said figures opening in one direction being formed into an eye and at the apexes of said figures opening in the opposite direction into a double hook, and said sections being alternately reversely ar- 125

ranged with the one-half diamond figures of one section matching the one-half diamond figures of the adjacent section to complete meshes of diamond-figure outline, and the 5 hooks at the apexes of the members of one set of alternate sections being engaged with the eyes at the apexes of the members of the other set of alternate sections, and the side members of said meshes defining substantially 10 continuous crossing diagonal lines extending throughout the fabric, said eyes being extended outwardly of the apexes of their contiguous one-half mesh-figures and said hooks being extended inwardly of the 15 apexes of their contiguous one-half mesh-figures and formed with spaced-apart but closely related longitudinal parallel side members.

5. A mattress fabric comprising a series 20 of parallel elongated wire sections interengaged with one another in series, each section being formed of a rod of wire bent zig-zag to define a series of corresponding alternately reversed space-meshes of the shape of 25 one-half of a diamond figure and said rod at

the apexes of said figures opening in one direction being formed into an eye and at the apexes of said figures opening in the opposite direction into a double hook, and said sections being alternately reversely arranged with the one-half diamond figures of one section matching the one-half diamond figures of the adjacent section to complete meshes of diamond-figure outline, and the hooks at the apexes of the members of one 30 set of alternate sections being engaged with the eyes at the apexes of the members of the other set of alternate sections, and the side members of said meshes defining substantially continuous crossing diagonal lines extending throughout the fabric, and said sections in pairs at the sides of the fabric being connected with each other by the hooking together of the meeting ends of the rods of which said sections are formed. 35

Signed at Brooklyn, in the county of Kings and State of New York, this 8th day of July, A. D. 1920.

OTTO J. GASAU.
